UNITED STATES PATENT OFFICE.

LEANDER D. BERGER, OF PHILADELPHIA, PENNSYLVANIA.

DESIGN FOR A CONDUCTOR-HOOK.

SPECIFICATION forming part of Design No. 22,384, dated May 2, 1893.

Application filed August 10, 1892. Serial No. 442,718. Term of patent 14 years.

To all whom it may concern:

Be it known that I, LEANDER D. BERGER, a citizen of the United States, residing at Philadelphia, in the county of Philadelphia and State of Pennsylvania, have invented a certain new Design for Conductor-Hooks; and I do hereby declare the following to be a full, clear, and exact description of the invention, such as will enable others skilled in the art to 10 which it appertains to make and use the same.

This invention has relation to designs for conductor hooks and consists in the novel construction and configuration of the same.

In the accompanying drawings illustrating 15 a conductor hook embodying my invention Figure 1 is a side view; Fig. 2 a front view; Fig. 3 a top view partially in section.

The conductor hook consists of two parts the tang A and the hook B. The tang A as 20 shown tapers from the hook A toward the point b, and is concaved on both sides throughout its entire length. The hook A is of a triangular configuration in cross section the

base of the triangle being toward the inner 25 surface of the hook, and the hook where joined to the tang being of smaller area than the tang. Its lower edge a, coincides with the surface of the concavities on the tang the hook portion being fluted throughout the greater 30 portion of its length as shown in the drawings. A shoulder C is formed at the junction of the tang and the hook by the outer end of the lower or bottom half of the tang.

The leading features of the design are the concaved tang and the fluted hook.

Having thus described my invention, what I claim is—

The design for a conductor hook as herein shown and described.

In testimony whereof I affix my signature in 40 presence of two witnesses.

LEANDER D. BERGER.
